UNITED STATES PATENT OFFICE

2,483,021

ROLL HEATING AND COOLING

Orion Ottis Oaks, Summit, N. J., assignor, by
mesne assignments, to Thermal Liquids, Inc.,
New York, N. Y., a corporation of Delaware

Application December 9, 1947, Serial No. 790,488

2 Claims. (Cl. 257—3)

1

This invention relates to a method and apparatus for temperature conditioning rolls and more particularly to the heating and cooling of rolls suitable for rolling metal; for paper making; for the manufacture of plastics; for mangles, and for other similar uses.

Heretofore various means have been proposed for heating and cooling rolls both directly and indirectly, but most of these require complicated apparatus of large size to heat or to cool to desired temperatures. Such apparatus is not only expensive, but relatively inefficient and much caloric content of the heat transfer medium is lost that would otherwise be available for heating or cooling the rolls.

I have found that by using a particular class of chemical compounds, the tetra-aryl ortho silicates, as the heat transfer medium that I can overcome most of the disadvantages of existing roll heating and cooling devices and provide a novel method and apparatus for roll heating at high temperatures and at low pressures and for roll cooling which will require relatively simple and light apparatus; which will be most efficient; and which will utilize a maximum of the caloric content of the transfer medium available for roll heating or cooling.

It is accordingly an object of the present invention to provide a novel method and apparatus for roll heating or cooling which uses a particular class of chemical compounds, the tetra-aryl ortho silicates, as the heat transfer medium.

Another object is to provide such apparatus which is of simple and light construction and which efficiently uses available heat or cold for roll heating or cooling.

Another object of the present invention is to provide such a method that can be readily, cheaply and easily utilized with existing apparatus.

Other and further objects of the present invention will appear from the following description.

The tetra-aryl ortho silicates are described in the Johnston Patent No. 2,335,012, dated November 23, 1943. As there described these compounds remain fluid at approximately 70° F. and boil in the neighborhood of 725° F. Within this wide temperature range these compounds are efficient heat transfer media readily absorbing and readily giving up heat or cold applied thereto. No super-atmospheric vapor pressures are generated in this temperature range so that the means utilized for circulating these compounds can be made of the simplest construction and of sufficient

2

strength for circulating purposes only without the application of more than nominal pressures.

The accompanying drawings show two of the many mechanical embodiments which my invention may take. These embodiments are shown and described hereinafter to illustrate my invention and should not be construed as defining or limiting the same, reference being had to the appended claims for this purpose.

10 In the drawings in which like reference numerals designate like parts,

Fig. 1 is a view of an embodiment of my invention as seen from the front with a portion of the lower roll broken away to show the novel means for internally heating the same;

Fig. 2 is a fragmentary cross-sectional view of a part of Fig. 1 on the line A—A thereof; and

Fig. 3 is another embodiment of my invention for use in roll heating or cooling.

20 In Figs. 1 and 2, 10 is a suitable machine base supported on legs 11 and carrying roll supports 12 and 13. A hollow roll supporting shaft 14 is carried by supports 12 and 13 and hollow roll 15 is mounted for rotation thereon. A second roll supporting shaft 16 is carried by supports 12 and 13 spaced from and parallel to shaft 14 and a second roll 17 is mounted for rotation thereon for cooperation with roll 15. An electric motor 18 mounted on base 10 drives roll 15 by any suitable means such as pulley 19, belt 20 and pulley 21, pulley 21 being secured to an axial extension 22 of roll 15. Axial extension 22 has pulley 23 secured thereto which drives roll 17 through belt 24 and pulley 25, pulley 25 being secured to axial extension 26 of roll 17. When it is desired to rotate rolls 15 and 17 in opposite directions, belt 24 may be crossed between pulleys 23 and 25 as shown.

40 A closed system employing tetra-aryl ortho silicate as the heat transfer medium is utilized to internally heat roll 15. As shown this system comprises a suitable boiler 27 heated by coal, oil, wood, gas, electricity or other suitable means for heating the tetra-aryl ortho silicate which may be heated up to approximately 725° F. without boiling. The heated tetra-aryl ortho silicate is taken from boiler 27 by pipes 28 and 29 and led through thermostatically controlled valve 30 and pipe 31 to hollow shaft 14, pipe 31 being coupled to shaft 14 at 32. An expansion tank 33 is provided for the closed system to take care of any expansion or contraction of the tetra-aryl ortho silicate during heating and cooling. A vacuum and pressure responsive relief valve 34 may also be provided as a safety feature opening into the sys-

tem and preset to open only under abnormal conditions of pressure or vacuum.

Hollow shaft 14 is provided inside roll 15 with a hollow extension 33 communicating therewith which carries a T coupling 34. Headers 35 and 36 extend from coupling 34 and are spaced from and are parallel to shaft 14. Headers 35 and 36 are provided with a plurality of nozzles 37 communicating with headers 35 and 36 and designed to flow heated tetra-aryl ortho silicate onto the upper and under side of roll 15 adjacent its line of rolling cooperation with roll 17, as best seen in Fig. 2.

A dam 38 is placed in hollow shaft 14 adjacent the opening of extension 33 into shaft 14 and forces the entire flow of heated tetra-aryl ortho silicate into extension 33. A downwardly extending hollow extension 39 is secured to hollow shaft 14 and in communication therewith within roll 15 and terminates adjacent the inner and lowest part of roll 15 to drain roll 15 of cooled tetra-aryl ortho silicate. A return pipe 40 is coupled to hollow shaft 14 at 41 and leads to a suitable pump 42. Pump 42 is driven by motor 18 through pulley 43, belt 44 and pulley 45. The discharge side of pump 42 is connected by pipe 46 to the return side of boiler 27. A by-pass 47 connects thermostatically controlled valve 30 and return pipe 40.

Thermostatically controlled valve 30 is actuated by the conventional bulb 48 in heat exchange engagement with roll 15 and connected thereto by tubing 49.

Fig. 3 illustrates an embodiment of my invention suitable for use when it is desired to heat or to cool roll 15. The structure of the rolls and the means for heating the tetra-aryl ortho silicate is the same as that of the embodiment shown in Figs. 1 and 2. A suitable absorption type refrigerating unit 50 having a conventional generator 51 and a reservoir 52 for tetra-aryl ortho silicate to be cooled is suitably positioned with respect to boiler 27. Couplings 53 and 54 and manually operable valve 55 are connected into pipe 29. Pipe 56 including manually operable valve 57 connects to coupling 53 and to generator 51. Return pipe 70 is provided with couplings 71, 72 and 73 and with manually operable valve 67 and connects to generator 51 and to pipe 40 at coupling 74. A thermostatically controlled valve 75 with a bypass 76 is connected into pipe 56 and bypass 76 connects to coupling 71. Valve 75 is actuated by bulb 77 in reservoir 52 which is connected to valve 75 by tube 78 in conventional manner. Cooled tetra-aryl ortho silicate is taken from reservoir 52 by pipe 62 through manually operable valve 63 to coupling 54. By-pass 47 is connected to coupling 54. Pipe 46 is provided with coupling 64. Pipe 65 connects coupling 64 through manually operable valve 66 to the return side of reservoir 52. A manually adjustable valve 58 and a coupling 59 are also connected into pipe 46. A pipe 79 including manually operable valve 68 connects to coupling 72 and to a suitable pump 80. The driving means for pump 80 is not shown. The discharge side of pump 80 is connected by pipe 81 through manually operable valve 61 to coupling 59.

With the embodiment of my invention set up as above described for Figs. 1 and 2 when it is desired to apply heat to roll 15 boiler 27 is fired and motor 18 is started. Actuation of motor 18 drives pump 42 and heated tetra-aryl ortho silicate is drawn from boiler 27 through pipes 28 and 29, valve 30 and pipe 31 into shaft 14 where it backs up against dam 38 and flows into coupling

34 and headers 35 and 36. From headers 35 and 36 the heated tetra-aryl ortho silicate flows out of nozzles 37 against the inner and upper side of roll 15 adjacent its line of rolling cooperation with roll 17 so that at the line of rolling cooperation roll 15 is given maximum heating. The heated tetra-aryl ortho silicate flows down the back and inner side of roll 15 against its direction of rotation and preheats that part of roll 15 approaching the area of contact of heated tetra-aryl ortho silicate flowing from nozzles 37. The used and partially cooled tetra-aryl ortho silicate collects at the lowest point of roll 15 and is drawn therefrom through extension 39, hollow shaft 14 and pipe 40 by pump 42, and return to boiler 27 by pipe 46.

Thermostatically controlled valve 30 is preset for the desired rolling temperature. Should the heated tetra-aryl ortho silicate admitted to roll 15 heat the same above this temperature bulb 48, which is in heat exchange relationship with roll 15, will actuate valve 30 to close pipe 31 to the flow of heated tetra-aryl ortho silicate and bypass the same through by-pass 47 back to boiler 27 until such time as roll 15 cools below the preset temperature of valve 30. Bulb 48 will then actuate valve 30 to close off by-pass 47 and open pipe 31.

Actuation of motor 18 not only drives pump 42 but rotates rolls 15 and 17 which cooperate to give the desired rolling action. It is to be understood that not only may roll 15 be heated in the manner just described but when desirable roll 17 may be similarly heated. Further, when desirable, the rolling action may take place between heated roll 15 and a fixed surface or a plurality of such heated rolls may be employed in any conventional manner.

The embodiment of my invention described with reference to Fig. 3 can be used to both heat and cool the rolls. When this embodiment is used to heat the rolls valves 63, 66 and 68 are closed and valves 55, 57, 58 and 61 are opened. The function of this embodiment is then similar to that of the embodiment of Figs. 1 and 2 but includes flow of heated tetra-aryl ortho silicate through generator 51 to keep the tetra-aryl ortho silicate in reservoir 52 cooled.

When it is desired to cool the rolls valves 55, 58 and 67 are closed and valves 51, 61, 63, 66 and 68 are opened. Heated tetra-aryl ortho silicate then continues to pass from boiler 27 to pipes 29 and 56 and to generator 51 and is returned from generator 51 to boiler 27 by pipe 70, pump 80, pipe 81 and pipe 46. The cooled tetra-aryl ortho silicate in reservoir 52 is circulated through pipe 62, when pump 42 is energized through valve 30 and pipe 31 to the roll and cools the roll. The tetra-aryl ortho silicate is removed from the roll through pipe 40, pump 42, pipe 46, pipe 65 and valve 66 and is returned to reservoir 52. Valve 30 may be preset to any desired temperature for cooling the roll and when the roll falls below this temperature bulb 48 actuates valve 30 closing pipe 31 and opening by-pass 47. The cooled tetra-aryl ortho silicate is then by-passed around the roll and returns to reservoir 52 through by-pass 47, pipe 70, pump 42, pipe 46 and pipe 65 until the temperature of the roll rises above that for which valve 30 is preset. Valve 30 then closes by-pass 47 and opens pipe 31 allowing cooled tetra-aryl ortho silicate to again be circulated through the roll. Valve 75 is preset for any desired temperature for the cooled tetra-aryl ortho silicate in reservoir 52 and when the tetra-aryl

ortho silicate is cooled below this temperature bulb 17 actuates valve 75 to by-pass generator 51 until the temperature of the tetra-aryl ortho silicate rises above the preset value. A close and accurate adjustment of the cold temperature of the roll is thus obtained.

It will now be apparent that by the present invention I have provided a novel method and apparatus for roll heating and cooling to high temperatures and to low temperatures at atmospheric pressures which uses a particular class of chemical compounds, tetra-aryl ortho silicate, as the heat transfer medium; which employs simple apparatus of light construction; which efficiently uses the caloric content of the medium available for roll heating and cooling; and which can be readily, cheaply and easily utilized with existing apparatus.

Changes to or modifications of these illustrative embodiments of my invention may now be suggested to those skilled in this art without departing from my inventive concept. Reference should therefore be had to the appended claims to determine the scope of this concept.

What is claimed is:

1. A system for internally heating a hollow roll using an organic silicate as the heating medium and including means for heating the organic silicate and a hollow roll, a hollow roll shaft upon which the roll is rotatably mounted, piping connecting the heating means and one end of said hollow shaft, a thermostatically controlled valve in said piping, piping connecting the other end of said hollow shaft and said heating means, circulating means for said organic silicate in said second named piping, means within the hollow roll receiving heated organic silicate from said hollow shaft and flowing the heated organic silicate against the inner surface of the roll, a by-pass between said valve and said second piping, said piping constituting a closed system, expansion

means for the organic silicate connected into the closed system above and adjacent to said heating means and normally closed pressure and vacuum relief means for said expansion means.

2. A system for internally cooling a hollow roll using an organic silicate as the cooling medium and including means for heating an organic silicate and a hollow roll, absorption-type refrigerating means for cooling an organic silicate including a generator, means for circulating heated organic silicate from the heating means to said generator, expansion means including normally closed pressure and vacuum relief means connected into said circulating means above and adjacent to said heating means, a hollow roll shaft upon which the roll is rotatably mounted, piping connecting said refrigerating means and one end of said hollow shaft, a thermostatically controlled valve in said piping, piping connecting the other end of said hollow shaft and said refrigerating means, circulating means for the cooled organic silicate in said second named piping, means within the hollow roll for receiving cooled organic silicate from said hollow shaft and for flowing the cooled organic silicate against the inner surface of the roll, and a by-pass between said valve and said second piping.

ORION OTTIS OAKS.
